UNITED STATES PATENT OFFICE.

EDWIN G. REID, OF OSAGE CITY, KANSAS, ASSIGNOR OF ONE-HALF TO CLINTON S. WOLFE, OF TOPEKA, KANSAS.

FOLDING CAR-STEP.

1,178,751.

Specification of Letters Patent. Patented Apr. 11, 1916.

Continuation in part of application Serial No. 5,443, filed February 1, 1915. This application filed April 15, 1915. Serial No. 21,522.

To all whom it may concern:

Be it known that I, EDWIN G. REID, a citizen of the United States, residing at Osage City, in the county of Osage and State of Kansas, have invented certain new and useful Improvements in Folding Car-Steps; and I do declare the following to be a full, clear, and exact description of the invention, such as will enable others skilled in the art 5 to which it appertains to make and use the same, reference being had to the accompanying drawings, and to the letters and figures of reference marked thereon, which form a part of this specification.

15 My invention relates to folding car steps, and has for its principal object to provide a device of this character which may be let down to assist passengers in entering or leaving a railway or like car, but which may 20 be nested beneath the permanently fixed steps when not in use and thereby provide an extension for the ordinary step which will be out of danger of interference when the car is in motion. In accomplishing this 25 object I have provided the improved details of structure, the preferred forms of which are illustrated in the accompanying drawings, wherein:—

Figure I is a perspective view of part of 30 a car platform provided with the usual steps and equipped with my improvement. Fig. III is an enlarged bottom perspective of part of a lower fixed step and my improved extension. Fig. IV is a rear perspective of a 35 part of the hanger mechanism of the extension step. Fig. IV is a vertical section of the same, showing the extension step hangers lowered and the step about to be lowered to functional position. Fig. V is a similar 40 view of the parts in nested position.

Referring more in detail to the drawings: 1 designates a railway car of ordinary construction, and 2 the usual car steps, which may be of any ordinary or suitable construction as the details thereof do not affect 45 my improvements.

Fixed to the bottom step 2 near the outer edges thereof are blocks 3 having facing grooves 4 that are preferably open at the back and closed at the front to provide for free sliding travel of a hanger frame in a rearward direction and for stopping the hanger at a determined point in its forward

travel, the front end of the block having bosses 3' at their faces that support the 55 hanger arms presently described and which have inclined forward ends 3'' against which said hanger arms are adapted to rest to brace the arms and to hold the same projected so that the steps may be supported 60 in advance of the permanent step when in functional position.

Slidably mounted in each of the grooves 4 are slides 5 which are connected and spaced by a cross bar 6 so that the slides may move 65 in unison in either direction and are braced inwardly to prevent their escape from their respective slides.

Pivotedly mounted on each of the slides 5 in front of the cross bar 6 is a hanger arm 70 9 which is pivotally suspended from its slide by a pin 10 and is connected with the relative arm at the opposite side of the step by a cross bar 11.

Pivotedly mounted on the hanger arms 9 75 are the step rails 13, each of which projects forwardly beyond the hangers, when in functional position, to carry the step 14 and each being provided with an upwardly and laterally offset stop 15 which is adapted for 80 engagement with the rear edge of the hanger arm to which its rail is connected, in order to limit the pivotal movement of the step and hold same in horizontal position when the step is lowered for use; the lower edge 85 of the rail being adapted to seat on the cross bar 11 as the stop engages the arm, so that both members serve to hold the step under the weight of a person. The step 14 extends forwardly a suitable distance and 90 preferably extends back of the hanger bar 11; the rear edge of the step plate being turned upwardly to form a back stop 17 that will prevent the foot of a passenger from moving over the rear of the step should 95 the passenger slip while using the step; it being apparent that the said back stop may also serve as a cover or shield for the step mechanism when the step is nested (Fig. V).

Pivotedly mounted on ears 19 on the back 100 of the hanger bar 11 are bell crank levers 20 the upper arms of which are provided with latch teeth 21, which are adapted for engaging the rear edge of a strap 22 that is fixed to the bottom of the lower car step 2 105 when the parts are nested, to lock the ex-

tension step in its nested position; the other arms 23 of the said levers being connected by a rod 24 which serves as a handle to unlatch the folding step and also as a weight 5 to automatically throw the latch into locking engagement with the strap. The folding step parts are protected when in nested relation, by a plate 25, which is fixed to the lower edges of the blocks 3 and extends 10 across the step to brace the blocks 3 apart to maintain the proper coöperation of the blocks with each other and the sliding parts.

In using the device, presuming the parts to be constructed and assembled as described, with the folding step nested beneath the fixed member, when the car stops to discharge or take on passengers an attendant arranges the folding step by first lifting on the bar 24 to unlatch the step and then 15 drawing the step outwardly so that the slides 5 may travel forwardly in the block grooves until the hanger arms have passed over the bosses 3-5 and may drop to functional position. When the hangers are 20 down the step 14 may be pivoted forwardly to extend the step; the stops 15 on the step rails engaging the rear edges of the hanger when the step is in horizontal position to maintain such position under weight of persons entering or leaving the car; the upturned back flange of the step serving as a 25 protection against the person slipping beneath the fixed step, when the inclined bosses 3' stop the hanger arm to hold the step advanced so that it may be conveniently utilized. When the car is ready to move, the attendant lifts the step proper to align it 30 with the hangers, lifts the free edge of the hangers until they are parallel with the bottom of the fixed step and moves the parts 35 backwardly beneath the protecting plate 25; the slides 5 traveling in the grooves in the blocks 3 to allow the parts to assume their nested position and the parts being moved 40 backwardly until they are completely nested between the step and plate 25. When the parts are in this position the handle rod is released and its weight throws the latch teeth back of the strap 22 so that the step is 45 held against accidental displacement and until the attendant again rocks the bar.

Having thus described my invention, what I claim as new therein and desire to secure by Letters-Patent, is:—

- 55 1. The combination with a fixed step, of grooved members suspended from said step, a slide adapted for travel in the grooved members, hangers suspended from said slides, and an extension step mounted on said hangers with the extension step hangers mounted to permit the same to travel with the slide and nest beneath the fixed step.
- 60 2. The combination with a fixed step, of grooved members suspended from said step, a slide adapted for travel in the grooved

members, hangers suspended from said slide, an extension step mounted on said hangers with the extension step hangers mounted to permit the same to travel with the slide and nest beneath the fixed step and a latch for retaining the parts in their nested relation. 70

3. The combination with a fixed step, of blocks suspended from said step and provided with facing grooves the said blocks having protuberances forming stop faces 75 near the front ends of the grooves, slides adapted for travel in the grooves, hangers pivotally connected with the slides and adapted for abutment against said stop faces, and an extension step mounted on the 80 hangers.

4. The combination with a step, of blocks suspended from the step and provided with grooves and having protuberances thereon forming stop faces adjacent the ends of the 85 grooves, slides adapted for travel in said grooves, hangers pivotally mounted on the slides and adapted for support on the protuberances and abutment against the stop faces, and an extension step mounted on the 90 hangers.

5. The combination with a step, of blocks suspended from the step and provided with grooves and having protuberances thereon forming stop faces adjacent the ends of the 95 grooves, slides adapted for travel in said grooves, hangers pivotally mounted on the slides and adapted for support on the protuberances and abutment against the stop faces, and an extension step pivotally 100 mounted on the hangers and adapted to fold relative thereto to nest with the hangers beneath the first named step.

6. The combination with a step, of means carried by the step for supporting slides, 105 slides supported by said means, hangers supported by said slides and comprising a crossbar, arms pivotally mounted on said hangers and comprising shoes adapted for abutment against said hangers with the 110 arms supported on the crossbar, and a step carried by said arms.

7. The combination with a step, of means carried by the step for supporting slides, 115 slides supported by said means, hangers supported by said slides and comprising a crossbar, arms pivotally mounted on said hangers and comprising shoes adapted for abutment against said hangers with the arms supported on the crossbar, a step carried by 120 said arms, bell crank arms mounted on the hangers and provided with hook members, a hand rail connecting said bell crank arms, and means on the first named step for engagement with the hook members on said bell crank arms. 125

8. The combination with a fixed step, of blocks fixed to the under face of said step and in spaced relation to each other; the said blocks having grooves on their inner 130

faces, slides adapted for travel in said grooves and for abutment in said grooves, hangers pivotally suspended from said slides, means for limiting the rearward movement of the hangers, a step pivotally mounted on the hangers, means on the step for engaging the hangers and for limiting the pivotal movement of the step, a stop on the rear edge of said step, and a plate fixed to the lower under edges of said blocks to space the latter and protect the step when the parts are lifted.

9. The combination with a fixed step, of blocks suspended from said step and having facing grooves, slides in said grooves, a hanger suspended from the slides, a step pivotally mounted on the hanger, latch levers pivotally mounted on the hanger, a rod connecting the latch levers, and a strap on the under face of the fixed step adapted

for engagement by said levers when the parts are nested.

10. The combination with a step, of blocks suspended from the step and provided with grooves and having protuberances thereon forming step faces adjacent the ends of the grooves, slides adapted for travel in said grooves, hangers pivotally mounted on the slides and adapted for bearing against the faces of said protuberances and an extension step mounted in said hangers, the faces of said protuberances being inclined to project the hangers forwardly, substantially as set forth.

In testimony whereof I affix my signature in presence of two witnesses.

EDWIN G. REID.
